(No Model.)

C. A. WRIGHT.

GILDER'S GOLD LEAF CARRYING APPARATUS.

No. 289,486.

Patented Dec. 4, 1883.

UNITED STATES PATENT OFFICE.

CHARLES A. WRIGHT, OF PHILADELPHIA, PENNSYLVANIA.

GILDER'S GOLD-LEAF-CARRYING APPARATUS.

SPECIFICATION forming part of Letters Patent No. 289,486, dated December 4, 1883.

Application filed May 4, 1883. (No model.)

To all whom it may concern:

Be it known that I, CHARLES A. WRIGHT, of the city of Philadelphia, county of Philadelphia, and State of Pennsylvania, have invented an Improvement in Gilders' Gold-Leaf-Carrying Apparatus, of which the following is a specification.

My invention has reference to apparatus to hold the gold-leaf adapted to gilders' use; and it consists in arranging the gold-leaf in a continuous layer and rolling it up with a roll of paper or other equivalent material; further, in supporting the said roll upon one end of a base, and providing therewith means to roll said paper off of one cylinder and on to another, exposing the continuous sheet of gold-leaf in the act; further, in providing apparatus as last set forth with a table or cushion, over which the paper runs in passing from one cylinder to the other, to enable the paper to be suitably supported to enable the gold-leaf to be readily cut; further, in providing said table with a measure, to enable the gilder to measure off any desired length of gold-leaf without the use of an auxiliary rule or measure; further, in spacing the roll of paper off to indicate leaves and books, whereby the gold-leaf-manufacturer can at once ascertain its contents and the gilder the quantity of gold used on any piece of work, and in details of construction, all of which are more fully set forth in the following specification and shown in the accompanying drawings, which form part thereof.

The object of my invention is to provide the gold-leaf in a continuous strip, instead of the small leaves now used, whereby the gilder may with more facility and rapidity perform a given quantity of work.

In the drawings, Figure 1 is a sectional elevation of my improved gold-leaf-carrying apparatus on line *xx* of Fig. 2, and Fig. 2 is a plan view of same.

A is the frame, and *B* are the cylinders or reels upon which the paper roll is wound. These reels may be made in any manner desired. For instance, the cylinder *b'* may be made of wood, with the axle *E* driven through, and the sides or flanges *b* may be of stamped sheet metal secured to said cylinder. The axles *E* are supported in brackets or standards *C*, having slots *D*, the mouths of which

are covered with pivoted caps *D'*, pivoted at *D*. By simply turning up the caps *D'* the reels or cylinders *B* may be removed or replaced. Any other form of bearings may be used. The ends of the axles *E* may be made square, as at *e*, or may have handles wherewith to turn the reels; but I do not deem it necessary. These reels are put under friction by springs *F*, secured to the frame *A* at *f*, and pressed up against the flanges of the reels, which friction may be increased or diminished by screws *G*.

H is the supporting and cutting table, and may be simply made of wood; but I prefer to make it of a base, *I*, with a covering of leather, chamois, or kid, *K*, with a filling, *J*, of cotton or equivalent material, as hair.

L is the roll of paper adapted to receive the gold-leaf, and consists of a long strip of paper divided off, as at *M*, throughout its entire length, the said divisions being sufficiently wide to take in a leaf of gold, and by numbering said divisions consecutively the number of leaves of gold placed in the book or used therefrom may be known. Every twenty-five of said divisions correspond to a book, and to indicate this I mark 1, 2, 3, 4, &c., at the end of twenty-five, fifty, seventy-five, &c., divisions; hence by referring to these numbers the number of books can be ascertained. If desired, the divisions may begin with No. 1 at the beginning of every new book. Sufficient paper is left undivided at each end of the roll to encircle the reels several times.

N is the gold-leaf, which is laid upon the paper roll, after the same is dusted with powder, in a continuous strip, the ends of the same overlapping each other, as indicated by dotted lines at *n*, so as to cause said leaves to join or unite with each other.

P is a scale marked or secured upon the cutting-table or its covering; or, if desired, it may be supported from the frame *A* and made to extend over into position, and it is equally self-evident that it might have been made on the edge of the paper roll *L*; but I prefer it on the table, as shown, as it then may be marked and the gold-leaf may always be brought to the zero-line.

In use the apparatus is worked as follows: The gold-leaf is laid upon the paper *L*, and then the two strips—gold and paper—rolled

upon the reel B. This reel is filled by the manufacturer of the gold-leaf, and is then placed in the supports at one end of frame A, preferably the right-hand side, and the other end is wrapped around the empty reel B at the left-hand side of the frame, the paper L, carrying the gold-leaf N, being supported by the table located between said reels, it being desirable that the top of said table be made on a level with the bottom of the wooden centers b' of the reels B, to prevent sagging of the paper. By turning the left-hand reel the paper is unwrapped from the right-hand reel and wound upon the left-hand reel, as indicated by the arrow, the tension-springs F preventing any undue revolution of said reels or sagging of the paper. The gold-leaf is cut off with a blunt knife in the usual way, and the line of cut may be guided by the division-lines. When all of the gold is used up, the paper L is then upon the left-hand reel, and that is sent back to the gold-leaf manufacturer and the right-hand reel is transferred to the left-hand supports C.

25 I do not limit myself to the construction shown, as my invention broadly comprehends the arrangement of the gold-leaf in a continuous strip and means wherewith to handle the same.

30 Having now described my invention, what I claim as new, and desire to secure by Letters Patent, is—

1. Gold-leaf for gilders' use formed in a long continuous strip, in combination with a 35 detachable support adapted to be folded or rolled up, substantially as and for the purpose specified.

2. Gold-leaf for gilders' use formed in a long continuous strip, in combination with a 40 portable support, the said strip being formed by arranging a number of small sheets with their edges overlapping upon each other, substantially as and for the purpose specified.

3. Gold-leaf for gilders' use formed in a 45 long continuous strip, in combination with a portable support, the said support being divided by lines into divisions indicating the number of leaves of gold as usually sold that the said continuous strip of gold would consist of, substantially as and for the purpose specified.

4. Gold-leaf for gilders' use formed in a long continuous strip, in combination with a 55 portable support, the said support being divided by lines into divisions indicating the number of leaves of gold as usually sold that the said continuous strip of gold would consist of, and divisions to indicate the number of books of gold-leaf contained in any length 60 of said strip, substantially as and for the purpose specified.

5. The combination of two reels or cylinders and a long strip of paper or cloth, arranged to be transferred from one of said reels 65 to the other, with a continuous strip of gold-leaf laid upon said paper, the said reels being

so arranged that the act of rolling the paper from one to the other exposes the gold-leaf, substantially as and for the purpose specified.

6. The combination of two reels or cylinders and a long strip of paper or cloth, arranged to be transferred from one of said reels to the other, with a support or table over which the paper is drawn, arranged between said reels, and a continuous strip of gold-leaf 70 laid upon said paper, the said reels being so arranged that the act of rolling the paper from one to the other exposes the gold-leaf, substantially as and for the purpose specified.

7. The combination of two reels or cylinders and a long strip of paper or cloth, arranged to be transferred from one of said reels to the other, with a support or table over which the paper is drawn, arranged between said reels, friction devices to prevent said reels 75 from readily rotating, and a continuous strip of gold-leaf laid upon said paper, the said reels being so arranged that the act of rolling the paper from one to the other exposes the gold-leaf, substantially as and for the purpose specified.

8. The combination of two reels or cylinders and a long strip of paper or cloth, arranged to be transferred from one of said reels to the other, with a support or table over which the paper is drawn, arranged between said reels, friction devices to prevent said reels 80 from readily rotating, means to vary the amount of said friction, and a continuous strip of gold-leaf laid upon said paper, the said reels being 85 so arranged that the act of rolling the paper from one to the other exposes the gold-leaf, substantially as and for the purpose specified.

9. The combination of two reels or cylinders and a long strip of paper or cloth, arranged to be transferred from one of said reels to the other, with a support or table over which the paper is drawn, arranged between said reels, a scale secured to or formed on said 90 table, and a continuous strip of gold-leaf laid 95 upon said paper, the said reels being so arranged that the act of rolling the paper from one to the other exposes the gold-leaf, substantially as and for the purpose specified.

10. The combination of reels B, supported 100 in brackets C, having adjustable bearings, frame A, table H, and paper strip L, substantially as and for the purpose specified.

11. The method of packing gold-leaf for 105 gilders' use, which consists in laying the gold-leaf upon a long strip of paper previously dusted with a powder to prevent its adhesion, and then rolling said paper and its gold-leaf up into a roll, substantially as and for the purpose specified.

120 In testimony of which invention I hereunto set my hand.

CHARLES A. WRIGHT.
